CLAIM

I claim the ornamental design for a collapsible and portable shape-sorting learning and development toy, as shown and described.

DESCRIPTION

FIG. 1 is an isometric view of the collapsible and portable shape-shorting learning and development toy embodying my new design;

FIG. 2 is a top plan view thereof;

FIG. 3 is a front elevational view thereof;

FIG. 4 is a left side elevational view thereof;

FIG. 5 is a right side elevational view thereof, seen in the direction of arrows 5 in

FIG. 6 is an upper rear view thereof, seen in the direction of arrows 6 in FIG. 5;

FIG. 7 is an upper front view thereof, seen in the direction of arrows 7 in FIG. 5; and,

FIG. 8 is a bottom plan view thereof, seen in the direction of arrows 8 in FIG.

The broken lines shown are included for the purpose of illustrating portions of the shape-sorting learning and development toy invention that form no part of the claimed invention.
